L. Yale, Jr.

Lock and Key.

U.S. 8,071.

Patented May 6, 1851.

UNITED STATES PATENT OFFICE.

LINUS YALE, JR., OF NEWPORT, NEW YORK.

LOCK AND KEY.

Specification of Letters Patent No. 8,071, dated May 6, 1851.

To all whom it may concern:

Be it known that I, LINUS YALE, Jr., of the town of Newport, county of Herkimer, and State of New York, have invented 5 a new and Improved Safety-Lock for Banks, Safes, Vaults, Stores, &c., called Yale's Self Detaching and Attaching Key-Lock; and I hereby declare the following to be a full and exact description, reference being 10 had to the annexed drawings, the same letters referring to like parts in the different figures.

In the front plate of the lock A, Figure 2, and even with it on the back or inside, is 15 inserted a wheel B, having a hub projecting sufficiently to reach through the door it is intended to secure. This wheel is pierced with a square mortise or key hole in its center, for the wrench part of the key to turn 20 it by. On the back near its outer edge, is inserted a driving pin C, Fig. 6, of sufficient strength to drive the key carriage D, Fig. 3, by means of the slot or mortise E, in which it works, thereby moving both the 25 key-carriage D and bolt-plate F, Fig. 5. Also in the back of said wheel is a countersink of the depth of the dovetail in the key, and sloped outwardly forming an inclined plane to force the pod of the key farther 30 into the key chamber, after it is detached.

Immediately behind and bearing against the front plate and wheel above described is the cut-off-plate or key-carriage D, Fig. 3, with an upright slot E, in which the driving 35 pin C works. Also a projection G, back, containing a chamber H, Fig. 7, for the pod of the key, in which it is carried to the latches N, Fig. 5. In the center of this key-chamber is a pin 1, Fig. 7, to drive back the 40 dowel in the key to the exact line of division, said chamber being open in the front end only when closed to the latches and open on the top only when closed in the front direction. Around the stud or pin in 45 its center is a coiled spring J, Fig. 7, which serves to keep the key pod pressed against the varied surface of the wheel. The projection on the back has also a notch on its corner by means of which and a latch here- 50 inafter described, it drives the bolt plate out in locking.

The bolt plate Fig. 5 slides against the back of the lock and is left projecting out of the lock sufficiently to receive the upright 55 bar on which are the bolts of the door. It has a track L, with shouldered stops on

which rides the key-carriage, said track projecting to the cut-off plate in front. It has also a pin M, on which are hung from latches N, and a hook latch O, said latches 60 being pressed down by springs P, on another stud or pin Q. Through this plate are two horizontal slots R and S, through which project respectively from the back plate Fig. 4 a ledge or shelf T, and a fence pin U. 65 The ledge or shelf serves to cover the inner opening of the key chamber, while it is open outwardly. The fence pin stops the latches, and therefore the bolt, unless the proper key occupies the chamber, said latches having 70 jaws to receive the fence pin when placed in line by the right key.

The back plate Fig. 4, is held in place by the corner pillars V, V, V, V, and contains the above described edge or shelf, and fence 75 pin projecting through the bolt plate to the cut off plate, as seen in section, Fig. 7.

W, the key, consists of five parts, Fig. 1. The pod X, containing the different planes corresponding to the latches of the lock, se- 80 cured to the shaft or wrench part Y, by a dovetail which is held from unseasonably disengaging by the dowel pin Z, driven through it by the spiral spring &, in the shaft secured there by the handle being 85 screwed in after.

To unlock, insert the key W through the square mortise in front, gently pressing to overcome the tendency of the spring in the key to throw it out. The stud in the key 90 chamber causes the dowel in the key to recede to the plane of the dovetail. Turn the key to the right and the motion thus given to the wheel moves, by means of the pin C, in the slot E, the key chamber and pod to 95 the right, bringing a blank surface of the cut-off plate across the key hole, and carrying the chamber and pod from under the shelf T, allowing the latches N, to fall upon the key thereby arranging them in a proper 100 manner to stride the fence pin U, allowing them both to move with the key carriage, being driven back by the projection on the back of the key carriage striking the stop on the track L, Fig. 5. To lock it, reverse 105 the motion of the key. The hook O, Fig. 5, having dropped into the notch in the corner of the key chamber forces the bolt outward until the latches are free from the fence pin U, when they are all raised up by 110 the shelf or ledge T, and leaving the bolt, the key-carriage continues moving forward

till the pod is redovetailed to the shaft. Withdrawing the key allows the pin which holds the dovetail to cross the plane of the joint and it is thus secured in place till 5 again inserted in the lock. Thus the proper key is applied to the lock with the same facility, as an ordinary key to an ordinary lock, without there even being an exposure of the latches to sight or feeling, thereby 10 preventing the possibility of its being picked—or the introduction of sufficient powder to open the lock.

What I claim as my invention and desire to secure by Letters Patent is—

15 1. The self detaching and attaching key for the purpose and object described.

2. In combination with said key I claim a powder proof key hole consisting of two or more parts so constructed that the outer part is turned by the key; while at the same time 20 the inner parts with the pod or pods of the key inclosed, are disconnected and moved entirely away from the outer, the same movement causing solid metal to occupy the space left and thus to effectually bar an entrance of any kind to the lock when its parts are in a position possible to be unlocked. 25

LINUS YALE, JR.
